UNITED STATES PATENT OFFICE.

LEONARD E. ASKE, OF DULUTH, MINNESOTA.

HEATER OR FUMER.

Application filed February 13, 1926. Serial No. 88,155.

My invention relates to heaters and fumers and has for its object the provision of an electric fumer of improved structure for heating, vaporizing, or fuming fuel oils, or 5 other liquids, or fluids. Another object is to provide an improved fumer for fuming comparatively heavy fuel oils of low volatility, and to provide an efficient fumer in which the electric heating element is substantially 10 protected from oxidizing fluids, and its endurance thereby greatly prolonged.

In the drawings, Fig. 1 is a central vertical longitudinal section of a fragment of a fuel manifold for an internal explosion engine, 15 showing in central vertical section my improved fumer positioned therein. Fig. 2, is a central horizontal section through said fumer. Fig. 3, is a top plan view of an absorbent element, or refractory sponge, 20 forming part of said fumer. Fig. 4, is a central vertical section of said sponge. Fig. 5, is a side elevation of a dry chamber jacket.

In the drawing, 1 is a fuel manifold having an enlarged chamber or catch basin 1^a formed thereon or secured thereto, preferably adapted to be closed at its outer end by a cover or plug 2 and gasket 2^a. Extending through said plug into the reduced portion 2^b of a recess 2^b formed in its inward 25 end, is an electric binding post 3, insulated from said plug in any suitable manner or by any suitable means, as by mica gaskets 4.

Upon the inward end of said post and in electric communication therewith is an electric high resistance element of any suitable 35 structure or material, as a carbon pencil or rod 5, preferably provided at its opposite end with a metallic conducting cap 5^a. Closely surrounded said element 5 is a sleeve 40 6 of suitable refractory material, preferably of non-porous insulating character, as cement.

Extending over said cap and sleeve is a close fitting vertically ribbed metallic jacket 45 7, preferably of copper, in electric communication with said cap or the upper end of said rod and extending downward into the enlarged portion of said recess 2^b. Said jacket is preferably provided at its lower end 50 with an outwardly directed annular flange 7^a extending to the side walls of the enlarged portion of said recess. A sealing ring 8 of any suitable material is preferably pressed down upon said flange in the space be-

tween said jacket and the side walls of the 55 enlarged portion of said recess, to prevent leakage of moisture from said recess to the interior of said jacket, or below said flange. Said ring is preferably of electricity conducting material, as copper, and adapted to 60 improve the electric communication between said jacket and said plug, constituting an electric ground for an electric circuit in which said rod is included.

Surrounding said jacket and spaced therefrom and extending from said ring to a plane a short distance above said jacket is an exterior sleeve 9 of any suitable material, 65 preferably of brass or copper.

A moisture absorbing element 10 of any 70 suitable refractory material, preferably asbestos fibre, is positioned in the space between said jacket and said exterior sleeve, and is adapted to contact with the outwardly directed ribs on said jacket and with the wall 75 of said exterior sleeve and to extend from said ring to a plane a short distance below the upper end of said jacket. Said absorbing element is preferably pressed into cylindrical form before being assembled in the 80 fumer. Said exterior sleeve is provided with an intake port 9^a intermediate of its ends, and said absorbing body or cylinder also preferably has an intake port 10^a formed therein adapted to register with the intake 85 port in said exterior sleeve.

A screen 11 of any suitable material or structure, preferably of cement, is preferably extended across the open upper end of said exterior sleeve. 90

An exhaust port or ports 7^b are preferably formed in said jacket adjacent to the upper end of said sleeve 6, to prevent the accumulation of any gas pressure which might form 95 in the chamber or contents within said jacket.

Said rod and binding post and jacket and plug are embodied in any suitable electric circuit with any suitable source of electricity, as a battery 12.

In operation, the heavy liquid particles 100 or globules of fuel drawn from a carburetor, not shown, into said manifold by the suction of engine pistons, not shown, all well known to the art, or condensed from moisture in the manifold when the engine is cooling, will 105 drop into said catch basin and flow through the intake port in said exterior sleeve into said absorbing element and thereby into con-

tact with the highly heated walls of said jacket by which said liquid particles will be fumed, the fumes will be conducted upward by the grooves between said ribs and will flow out of said fumer through said screen and into said manifold, whence they will be drawn into the cylinders of the engine in proper condition for use. The upper end of said fumer preferably extends slightly above the floor of the body portion of said manifold so as to prevent flooding the upper or exhaust end of said absorbent body and avoid any danger of the fumes being re-condensed by an overhead flood of liquid.

15 Said invention is especially effective, useful and economical in starting a cold engine and in conserving fuel at idling speeds and for preventing damaging quantities of liquid fuel from reaching the engine cylinders and 20 seeping into the crank case and diluting the lubricating oil.

It is obvious that said structure may be modified or altered in certain particulars within the scope and spirit of certain of my 25 claims.

What I claim is:

1. In an electric heater or fumer, the combination of an electric resistance element, a close fitting sleeve of refractory material surrounding said element intermediate of its ends, a close fitting metallic jacket encircling the sides of said sleeve and extending over the upper end of said resistance element, an exterior metallic sleeve encircling the sides of said jacket and spaced therefrom, means for tightly closing the space between the lower ends of said exterior sleeve and said jacket to form a fluid tight bottom for said space, a refractory absorbing element positioned above said bottom in the space between said exterior sleeve and said jacket, and an electric binding post electrically connected to the lower end of said resistance element, said exterior sleeve having an intake port formed therein for admitting fluid to said absorbing element.

2. In an electric heater or fumer, the combination of a plug having a recess formed in one of its ends, an electric binding post extending through the opposite end of said plug into said recess, means for insulating said post from said plug, an electric resistance member erected upon said post and adapted to electrically communicate therewith, a close fitting sleeve of refractory material encircling said resistance member intermediate of its ends, a close fitting metallic jacket vertically ribbed upon its outer face encircling the sides of said sleeve and extending over the upper end of said resistance member in electric series therewith, said jacket contacting with said plug within said recess, means extending from the side wall of said jacket to the wall of said recess to seal the bottom of the space between said

jacket and said wall, a refractory absorbing element closely encircling the sides of said jacket and extending from said sealing means to a point near the upper end of said jacket, and an exterior metallic sleeve encircling said absorbing element and extending from said sealing means to a point above said absorbing element.

3. In an electric heater or fumer, the combination of a source of electricity, a high resistance member in circuit with said source, a close fitting refractory sleeve encircling said resistance member intermediate of its ends, a close fitting metallic jacket encircling said sleeve and adapted to constitute one of the conductors of said circuit, a refractory absorbing element applied to the outer face of said jacket, means for holding said absorbing element in operative position, and means for conducting liquid to said absorbing element.

4. In an electric heater or fumer, the combination of a high resistance electric conductor, a sleeve of refractory material encircling said conductor intermediate of its ends, an electric conductor jacket encircling said sleeve, electricity conducting means adapted to electrically connect said jacket to said sleeve, refractory absorbing means applied to the outer face of said jacket, and an external sleeve encircling said absorbing means.

5. In an electric heater or fumer, the combination of a source of electricity, a high resistance electric conductor and a metallic jacket therefor in circuit with said source, a refractory sleeve interposed between a portion of said jacket and said conductor, refractory absorbing means applied to the outer face of said jacket, and means for preventing gravity leakage between said absorbing means and the interior of said jacket.

6. In an electric heater or fumer, the combination of a source of electricity, a high resistance electric conductor in circuit with said source, a refractory sleeve for said conductor, a ribbed and grooved jacket for said conductor and sleeve, said jacket being included in said circuit, refractory absorbing means applied to the outside face of said jacket, and means for inclosing said absorbing means, said inclosing means having intake and exhaust ports formed therein.

7. In a heater or fumer, a jacket having a grooved and ribbed outer side wall and a reduced closed end, said jacket being open at its opposite end.

8. In a heater or fumer, the combination of an electric conductor, a refractory insulating sleeve for said conductor encircling the same intermediate of its ends, and a jacket encircling said sleeve, said jacket extending over one end of said conductor and being electrically connected thereto.

9. In an electric heater and fumer, the

combination of an electric resistance member, a refractory insulating member encircling said resistance member intermediate of its ends, a ribbed and grooved jacket encircling 5 said sleeve, said jacket extending over one end of said resistance member and being electrically connected therewith, a refractory

absorbing member applied to the outer face of said jacket, and means for inclosing said absorbing means, said inclosing means having intake and exhaust ports formed therein.

In testimony whereof, I hereunto affix my signature.

LEONARD E. ASKE.
